WINDOW DISPLAY UNIT

Joseph L. Hogan, San Francisco, Calif.

Application December 18, 1948, Serial No. 150,226

Term of patent 14 years

(Cl. D80—9)

To all whom it may concern:

Be it known that I, Joseph L. Hogan, a citizen of the United States and a resident of the city and county of San Francisco, State of California, have invented a new, original, and ornamental Design for a Window Display Unit, of which the following is a specification, reference being had to the accompanying drawings, forming a part hereof.

Fig. 1 is a front elevational view of a window display unit, showing my new design; and

Fig. 2 is a top plan view thereof.

The dominant features of my design reside in the portions shown in full lines.

I claim:

The ornamental design for a window display unit, as shown and described.

JOSEPH L. HOGAN.
